UNITED STATES PATENT OFFICE.

ERNEST B. PERRY AND WILLIAM BASSETT, OF BAY CITY, MICHIGAN,
ASSIGNORS TO INDUSTRIAL WORKS, OF BAY CITY, MICHIGAN.

TAKE-UP DEVICE FOR HOISTING-BUCKETS.

SPECIFICATION forming part of Letters Patent No. 769,232, dated September 6, 1904.

Application filed May 23, 1904. Serial No. 209,350. (No model.)

To all whom it may concern:

Be it known that we, ERNEST B. PERRY and WILLIAM BASSETT, citizens of the United States, residing at Bay City, in the county of Bay and State of Michigan, have invented certain new and useful Improvements in Take-Up Devices for Hoisting-Buckets; and we do hereby declare the following to be a full, clear, and exact description of the invention, 10 such as will enable others skilled in the art to which it appertains to make and use the same.

This is a device for steadyng hoisting-buckets of cranes and like machines, and pertains more particularly to means for preventing 15 rotation of the bucket while being hoisted and consequent twisting of the hoisting ropes or cables.

The invention consists in certain mechanisms designed to attain these results.

20 The apparatus is attached to the hoisting-shaft or other suitably-located revolving part of the hoisting mechanism.

The invention consists in the devices illustrated in the accompanying drawings, in 25 which—

Figure 1 is a side elevation of a locomotive-crane to which our invention is applied. Fig. 2 is a vertical section broken away in part, the section being taken parallel with the axis 30 of the hoisting-shaft. Fig. 3 is a vertical section taken on the line $y-y$ of Fig. 2. Fig. 4 is a top plan view of the parts shown in Fig. 2, the brake-band being omitted. Fig. 5 is a detail of the bracket that supports one 35 of the pawls. Fig. 6 is a vertical section on the line $x-x$ of Fig. 2; showing the relative arrangement of the ratchet-wheels that control the movement of the bucket-steadyng cable.

40 As is clearly shown in the drawings, the invention consists in the following elements: A drum 1 is revolvably mounted on the hoisting-shaft 2 or other suitably-revolving shaft of the hoisting-engine, and to the drum is secured the steadyng-cable 3, the outer end of which is secured to the hoisting-bucket 4. The cable 3 may be guided in any suitable manner, as by means of an idler-pulley 5, carried by the crane-jib. When the bucket is

lowered, the cable 3 pays out from the drum 1, which revolves loosely on its shaft. Its revolution is retarded, however, by means of a band-brake 7, carried by a brake-face 7^a on the drum. The ends of the band-brake are mounted on the face of the ratchet-wheel 8, 55 which is mounted to revolve freely on the shaft 2. To prevent rotation of the wheel 8 while the cable 3 is being paid out and to thereby bring into action the resistance of the brake 7, we provide the pawl 9, adapted 60 to engage the teeth of the ratchet 8 and prevent its rotation while the cable is being unwound from the drum. The pawl 9 is preferably mounted on the bracket 9^a, bolted to the machine-frame. One end of the brake-band 7 passes through a lug 8^a, carried by the wheel 8, and has at its end a nut 8^b. Between the nut and the lug 8^a is a compressible spring 8^c, the tension of which may be regulated by the nut, thereby increasing or decreasing frictional resistance between the brake-band 7 and the drum 1, and consequently increasing or decreasing the maximum pull that can be exerted by the drum while the bucket is being lowered. In practice this resistance is adjusted to keep the 70 bucket steady under normal conditions of load and speed of hoisting.

It will be seen that the operation of the drum and the cable 3 so far as above described 80 is independent of the movement of the shaft 2, which may be going fast or slow and yet have no appreciable effect on the pull exerted by the cable 3 upon the bucket 4. When the bucket is being hoisted, it is necessary to keep 85 the requisite tension in the cable 3 and at the same time to wind up the cable at a speed corresponding to the speed with which the bucket is raised. From Figs. 2 and 3 it will be seen that the brake-band 7 will permit the drum 90 to slip if the pull on the cable is greater than a predetermined amount, and this condition exists whether the wheel 8 is revolving or whether it is held stationary by the pawl 9. If it revolves in the direction indicated by the 95 arrow in Fig. 3, it will wind up the cable 3 until the resistance on the cable equals that at which the brake-band 7 is set, and continued

movement of the wheel 8 will result in the band 7 slipping, thus retaining the predetermined pull on cable 3.

To revolve wheel 8 when the bucket is hoisted, and thereby take up the slack and maintain the desired tension in cable 3, we provide on the shaft 2 a keyed ratchet-wheel 10. (Shown in Figs. 2, 4, and 6.) The teeth of wheel 10 are inclined oppositely from those of wheel 8 and are engaged by the pawl 11, pivotally secured, by means of a pin 12 or otherwise, to the face of the wheel 8, as shown in Fig. 6. If shaft 2 turns in the direction indicated by the arrow in Fig. 6, pawl 11 locks wheels 8 and 10 together, causing the brake-band 7 to revolve, carrying with it drum 1 until the resistance of the cable 3 overcomes the friction of the brake-band, and thereafter the band slips around its bearing-face 7^a, serving to maintain tension in the cable, as previously described. When the shaft revolves in the opposite direction, pawl 11 is inoperative and wheel 8 is prevented from revolving by pawl 9, which is carried by the bracket 9^a or any other suitable stationary support.

By the means above described we have produced a take-up device that maintains constant tension on the bucket-steadying cable regardless of movement of the shaft 2, yet so constructed that only a predetermined amount of pull can be exerted by the steadyng-cable, thus insuring steadiness and uniform movement of the bucket in its work of hoisting and lowering.

What we claim as our invention, and desire to secure by Letters Patent, is as follows:

1. In a steadyng-device for hoisting-buckets and the like, the combination of a cable secured to the bucket; a winding-drum for said cable; said drum being loosely mounted on a revoluble shaft; a brake-band engaging said drum; a ratchet-wheel loosely mounted on said shaft and carrying the ends of said brake-band; a pawl carried by a fixed support and engaging said ratchet-wheel; a pawl pivotally mounted on said ratchet-wheel; together with a second ratchet-wheel keyed to said shaft and adapted to be engaged by said pawl.

2. In a steadyng-device for hoisting-buckets, and the like, the combination of a cable secured to the bucket; a winding-drum for said cable; said drum being loosely mounted on a revoluble shaft; a ratchet-wheel loosely mounted on said shaft; a friction-brake carried by said ratchet-wheel and adapted to engage said drum with a predetermined amount of frictional resistance; a pawl carried by a

fixed support and engaging said ratchet-wheel; a pawl pivotally mounted on said ratchet-wheel; together with a second ratchet-wheel 60 fixed to said shaft and adapted to be engaged by said pawl.

3. In a steadyng-device for hoisting-buckets, and the like, the combination of a cable secured to the bucket; a winding-drum for said cable, said drum being loosely mounted on a revoluble shaft; a ratchet-wheel loosely mounted on said shaft; a friction-brake carried by said ratchet-wheel and adapted to engage said drum with a predetermined amount 65 of frictional resistance; means for adjusting the frictional resistance of said brake; a pawl carried by a fixed support and engaging said ratchet-wheel; a pawl pivotally mounted on said ratchet-wheel; together with a second 70 ratchet-wheel fixed to said shaft and adapted to be engaged by said pawl.

4. In a steadyng-device for hoisting-buckets and the like, the combination of a cable secured to the bucket; a winding-drum for said cable, said drum being loosely mounted on a revoluble shaft; a wheel loosely mounted on said shaft; a friction-brake carried by said wheel and adapted to engage said drum with a predetermined amount of resistance; a locking 80 device carried by a fixed support and adapted to engage said wheel, said device being adapted to permit the wheel to rotate in one direction only; a second wheel fixed to said shaft; and a locking device carried by 85 said wheel, said last-mentioned locking device being adapted to rotate the loosely-mounted wheel in one direction only, for the purposes set forth.

5. In a steadyng-device for hoisting-buckets and the like, the combination of a cable secured to the bucket; a winding-drum for said cable, said drum being loosely mounted on a revoluble shaft; a friction-brake mounted to revolve loosely around said shaft and adapted 90 to engage said drum with a predetermined amount of frictional resistance; means for locking said brake against rotation in one direction; together with means carried by said shaft for rotating said friction-brake in one 95 direction only, for the purposes set forth.

In testimony whereof we affix our signatures in presence of two witnesses.
